BORING TYPE CONTINUOUS MINER BIT MOUNTING DEVICE

Clarence H. Brown, Chicago, Ill., assignor to Goodman Manufacturing Company, Chicago, Ill., a corporation of Illinois

Application April 21, 1958, Serial No. 729,686

4 Claims. (Cl. 262—33)

This invention relates to improvements in cutters for coal and the like and more particularly relates to an improved mounting means for the cutters of a continuous mining machine.

In continuous mining machines of the boring type, due to the continuous operation of the machine, the cutter bits rapidly become dull and must be changed quite frequently, particularly where the machine is operating in coal having impurities such as sulphur balls therein. The cutter bits, heretofore, have been individually supported on annularly traveling supports and have been held in place by set screws and the like, or by the taper of the shank of the bit and the socket therefor. While such holding means have been generally satisfactory insofar as holding the bit in place is concerned, each bit must be individually removed from its socket, which is necessarily a time consuming process particularly where the bits may become jammed in their sockets.

A principal object of the present invention is to provide an improved mounting means for the bits of a continuous mining machine, mounting the bits in clusters for replacement as a unit.

A further object of the invention is to provide a simplified form of bit mounting means for a continuous mining machine, which is readily detachable from the rotary cutter support for the machine and accommodates the replacement of dull bits with sharp bits in a cluster.

A still further object of the invention is to provide a cutter block for a continuous mining machine so arranged as to clamp a cluster of bits thereto and held in position on the cutter support of the machine by a single readily detachable fastening means.

These and other objects of the invention will appear from time to time as the following specification proceeds and with reference to the accompanying drawings wherein:

Figure 1 is a fragmentary front end view of the boring head of a continuous mining machine showing one of the bit mounting means in vertical section, with the bits broken away and shown in section;

Figure 2 is an end view of the bit mounting means shown in Figure 1, looking substantially along line 2—2 of Figure 1 with certain parts of the mounting means and bit support shown in section in order to illustrate the fastening means therefor;

Figure 3 is an enlarged fragmentary sectional view taken substantially along line 3—3 of Figure 2; and

Figure 4 is a fragmentary plan view of the cutter support and the bit mounting means therefor.

In the embodiment of the invention illustrated in the drawings, reference numeral 10 generally designates a rotatable boring head for a boring type of continuous mining machine. The boring head 10 may be of a well known form commonly used in boring continuous mining machines which make boring cuts in a coal face as the boring head is rotatably driven and axially fed into the coal face, so need only herein be shown and

described in sufficient detail to render the present invention readily understandable.

The boring head 10 includes a radial arm 11 extending radially from a central hub (not shown) and having a cutter support 12 extending outwardly therefrom in radially spaced relation with respect to the hub and a second cutter support 13 spaced radially outwardly from the cutter support 12.

The cutter supports 12 and 13 are each of a similar construction, and are in the general form of plates welded or otherwise secured to the arm 11 and extending forwardly therefrom and bent intermediate their ends in the form of a flat angled V in end view. The angles between the bent portions of the plates are such as to support cutter blocks 15 carrying clusters of cutter bits 16 on said supports, to support the cutter bits to conform to the annular path of travel of said cutter support and cut concentric annular kerfs in the coal face.

The cutter support 12 is herein shown as having a wedge 17 on the outer side thereof shaped to enter the kerf cut by the bits 16 and break down the core between the supports 12 and 13.

The cutter bits 16 are each of a similar construction, and as herein shown include a central boss 19 having parallel forward and rear faces having a shank 20 projecting therefrom having a hardened cutter tip 21 on the forward end thereof. The cutter tip 21 may be recessed in the advance face of the shank and may be made from an abrasive resistant hardened cutting material, such as a tungsten carbide. The shanks 20 are pitched at varying angles with respect to the boss 19 to position the cutting tips 21 to cut clearance for the cutter, as shown in Figure 2. Each boss 19 has a central apertured portion 22 for receiving a through bolt 23 for mounting a cluster of bits on the block 15 as will hereinafter be more clearly described as the specification proceeds.

The cutter block 15 is saddle-shaped in cross-section and has an outer head or block portion 24 having parallel legs 25 extending therefrom, engageable with opposite parallel faces of the associated cutter bit support 12 or 13.

As shown in Figure 4, the block portion 24 has a series of bit receiving slots 26 therein for receiving the bits 16 and clamping the bits to said block upon tightening of a nut 28 on the end of the through bolt 23. Each slot 26 is shouldered at its inner end, as indicated by reference numeral 27, to limit inward movement of the associated bit 16 and accommodate the apertured portions of the bits to be aligned with the through bolt 23. The bit engaging slots 26 have communication with cut-away portions 29 in the legs of the block 15 to impart resiliency in the block 15 and head 24 thereof, to accommodate opposite faces of the slots 26 to be drawn into clamping engagement with opposite faces of the heads or body portions 19 of the bits, to clamp the bits in position upon tightening of the nut 28 on the end of the through bolt 23, and to exert a pressure on said nut to hold said nut from loosening during operation of the boring head. It will here be noted that the advance bit engaging slot 26 has communication with cut-away portions 30 in the legs 25 and that the cut-away portions 30 are shorter than the cut-away portions 29 to provide sufficient stock in the legs 25 for retaining apertures 31 therein.

A single locking key or pin 33, insertable through the retaining apertures 31 in the legs 25 and an aperture 35 in the bit support 13, is provided to retain the block 15 to said support. The pin 33 is shown as having a head 36 on one end thereof, engageable with the outer face of a leg 25, and as having an annular recess 37 spaced inwardly of the head 36 and inwardly of the inner margin of the leg 25, which is engaged by a spring

pressed detent 39, to retain the pin 33 in place. The detent 39 is slidably guided in the support 12, in a guide slot 40 and is spring pressed into engagement with the annular groove 37 by a spring 41, seated within said guide slot. The guide slot 40 is herein shown as being a drilled hole and as opening to an outer face of the support 12.

The detent 39 has an annular recess 43 therein registering with the cut-away portion 30 to accommodate a screwdriver or the like to release said detent from the annular groove 37, to accommodate removal of the pin 33 when it is desired to replace the block 15 and a cluster of dull bits 16 with another block having a cluster of sharp bits carried therein.

The outer faces of the supports 12 and 13 are provided with back-up shoulders 44 abutted by the rear faces of the block portion 24 of the blocks 15 and so spaced along the supports with respect to the apertured portions 31 and 35 as to stop movement of the block portions 24 along the supports when the apertured portions 31 and 35 are in alignment with each other, and to thereby align the apertured portions 31 of the blocks with the apertured portion 35 of the support, to accommodate the locking pins 33 to be readily placed therein. The back-up shoulders 44 besides locating the apertures 31 and 35 also take a part of the cutting reactions, as shown in Figure 4, showing the horizontal components of force F on the cutter bits balanced by the reactions R₁ and R₂ on the back-up shoulder 44 and the pin 33 or the wall of the aperture 35.

It may be seen from the foregoing that a simple and efficient bit mounting has been provided, mounting the bits of a continuous mining machine to be removed and replaced in clusters. It may further be seen that the bits are held in position in their bit blocks by a single clamping device such as a through bolt and that the block with its cluster is simply mounted on the cutter support and retained in position thereon by a single pin.

While I have herein shown and described one form in which my invention may be embodied, it should be understood that various modifications and variations of the invention may be effected without departing from the spirit and scope of the novel concepts of the invention as defined by the claims appended hereto.

I claim as my invention:

1. In a cutter device for cutting coal and the like, a bit supporting block having an outer block portion having parallel spaced legs extending therefrom adapted to extend along opposite sides of a movable support, said block portion having a plurality of bit receiving slots therein opening to the outer side thereof and having oppositely facing bit engaging faces adapted to engage opposite faces of a series of cutter bits, with leg portions each having cut out portions in communication

with said slots and extending along said leg portions for a substantial portion of the length thereof to impart resiliency to said block portion, and clamping means for clamping said bit engaging faces with the cutter bits to retain the cutter bits in position on said block in a cluster.

2. A cutter device constructed in accordance with claim 1, in which the clamping means includes a through bolt extending longitudinally through the block portion and the cutter bits.

3. In a bit mounting device particularly adapted for the boring heads of continuous mining machines and the like for mounting a series of bits in a cluster including a cutter arm having a cutter support extending forwardly therefrom and movable in an annular path, a saddle-like block adapted to be mounted on said support and having an outer bit clamping block portion and parallel spaced legs extending therefrom and adapted to extend along opposite sides of said support, said block portion having a plurality of slots therein opening to the outer side thereof, each slot having facing bit engaging surfaces, said legs each having cut-away portions extending for a greater portion of the length thereof in communication with said slots and providing resiliency in said block portion, a through bolt extending through said block portion and the cutter bits in said slots and clamping said bit engaging faces to the associated cutter bits therein, and means for mounting said block on said support and for retaining said block from tipping with respect to said support comprising a stop on said support engageable with a rear face of said block, and a pin and apertured connection between said legs and said support adjacent the advance end of said block and spaced inwardly along said support toward the inner end portions of said legs.

4. A bit mounting device in accordance with claim 3, in which the pin and apertured connection includes apertured portions in said legs and support registering upon engagement of said support with said stop, a pin adapted to extend through the apertures of said apertured portions and a detent pin for retaining said pin in position and accessible through one of said cutaway portions.
